UNITED STATES PATENT OFFICE

94,237

DESIGN FOR A COLLAR HOLDER

Kirk C. Rupp, New Castle, Pa.

Application September 25, 1934, Serial No. 53,394

Term of patent 7 years

To all whom it may concern:

Be it known that I, Kirk C. Rupp, a citizen of the United States, residing at New Castle, in the county of Lawrence and State of Pennsylvania, have invented a new, original, and ornamental Design for Collar Holders, of which the following is a specification, reference being had to the accompanying drawing, forming a part thereof.

What I claim, is—

The ornamental design for a collar holder substantially as shown.

KIRK C. RUPP.
